In Switzerland May 27, 1932

8 Claims. (Cl. 230—137)

This invention relates to compressors and pumps, such, for example, as the compressors used in refrigerating apparatus. It relates more particularly to a device of this kind which operates by means of inertia.

The principal object of the present invention is to provide a simple device which operates with very little vibration and therefore does not cause objectionable noise.

10 Another object of this invention is to prevent the chattering and other vibrations during the starting or stopping of the machine.

Other objects, and the manner in which they are attained, will appear from the following description.

One embodiment of the invention is diagrammatically represented in the drawing, in which

Figure 1 is a longitudinal section through the compressor, and

20 Figure 2 is a cross-sectional view of the compressor.

Briefly explained, a compressor or pump according to the present invention comprises three distinct structures. The stator (second structure) and the rotor (first structure) of an electro-motor are arranged with their axes of rotation displaced relatively to each other, the rotor encircling the stator. The rotor is supported in a ball-bearing secured to a bracket from which the apparatus is suspended, and is rotatable about its axis of symmetry. The stator is supported in a ball-bearing arranged on the rotor, but is prevented from rotating about its axis. When current is supplied to the electro-motor, the rotor is caused to rotate relatively to the bracket and the stator. Due to the displacement of the axes, the stator is moved bodily in a circular path, the radius of which is the distance of displacement between the two axes, its center being located on the axis of rotation of the rotor.

The third structure is contained in housing parts connected to the stator. A displacer or eccentric piston arranged in the interior of the working chamber is swung around centrifugally therein by the motion of the stator in its circular path. Then the actual work, e. g., the compression of the medium supplied to the working chamber, is performed by means of inertia or mass forces.

50 More specifically, the driving system I consists of the bell-shaped bearing-housing 1, the motor casing 2 with the rotary part 3 of an electric motor, and the bell-shaped casing part 4. The three housing parts 1, 2 and 4 are held together by means of nuts and bolts 5 and 6. The lumens,

inside bores or cylindrical inner surfaces, both of the motor housing 2 and of the bell-shaped housing part 4 are eccentrically arranged with respect to their outer surfaces, which latter are in the form of surfaces of rotation, so that the center of gravity of these two housings does not coincide with the axis of symmetry of their outer surfaces. Each of the housing parts 1, 2 and 4 is suspended by means of bolts 7 from the disc 8 with a ring 9 made of a resilient material (rubber, for instance) interposed between the lower bolt-heads and the member 1. Mounted in the disc is a ball-bearing 10, by means of which the entire machine is suspended from the bolt 13 connected to the fixed support 12 by means of yoke 11.

The system II to which is imparted a translational motion, comprises the stator 15 of an electromotor shrunk on a shaft 14, housing parts 16, 17 and 18 of the actuating mechanism, and a disc 20 which defines and contains the working-chamber 19, and is mounted, by means of ball bearings 28 and 29, in the driving system I in such a manner that the axis of symmetry A of the external boundaries of the driving system I, and the axis of symmetry B of the system II, to which a translatory motion is imparted, are spaced apart a distance *a*. Through the conduit 21 the medium to be compressed is inducted, and through conduit 22 it is abducted. Conduit 23 serves as a lubricant-feed line. Each of these conduits is made 30 resilient, and connected at one end with the fixed base 12 and at the other end with the system II.

The system III which directly performs the actual compressing, comprises a displacer or eccentric piston, 24, and flyweights 25 and 26 rigidly 35 fixed and connected to the displacer on either face thereof. The axis of symmetry C of the system III is offset by a distance *b* from the axis of symmetry of the system II.

When electric energy is supplied to the electric 40 motor (comprising the stator 15 and the rotor 3) through the leads 44, the current flows through the brushes 45, the slip rings 27, the leads 46, the leads 47, and therefrom partly through the brush 48 to the commutator 49, and partly to the field coils 50; the current returns partly from the commutator 49 through the brush 52, and partly from the field coils 50, through the leads 51, the leads 46, the slip rings 27 to the brushes 45. A 45 rotary moment is then set up between the driving system I and the system II which moves along a circular path, which moment causes both systems to tend to rotate, one relatively to the other. Since the translatory moving system II is pre-

vented from rotating due to the conduits 21, 22, 23, and the driving system is mounted upon the ball-bearing 10, the driving system I starts rotating. Since the axis B of the two ball-bearings 28 and 29 is offset relatively to axis A a distance and parallel thereto, the system II executes, during the rotation of the driving system I, a movement of translation over a distance a , constituting the diameter of the stroke. The system II, therefore, describes, with its axis B, a circle Q about the axis A of system I.

With an eccentric arrangement of the components of the driving system I, the center of gravity of the compressor as a whole aligns itself with the axis of symmetry A of the surface of the driving system I, due to the eccentric arrangement of the two systems II and III, so that with undisturbed rotation it turns upon itself, for the reason that its axis of symmetry is at the same time the axis of rotation of ball-bearing 10. The surface therefore has the semblance of a cylinder rotating on itself, which on coming into contact with some other object, gives rise to no danger of knocking and does not cause the surrounding air to vibrate at audible frequency.

The translatory movement of system II centrifugally casts the work-performing system III around the inner periphery of the housing part 18, in such a way that the two flyweights 25 and 26, formed as solids of revolution, roll upon the inner cylindrical surface of housing part 18. During this motion the displacer body 24 describes, with its axis of symmetry C, a circle R with the axis of symmetry B of system II as its center. The slide-plate 30 during this motion of the displacer body 24, reciprocates, e. g. by spring action (not shown), which spring may be inserted within the slot in which the plate 30 moves, with one of its edges continuously contacting with the cylindrical surface of the displacer 24. The faces of the flyweights 25 and 26 contacting disc 20, are adjusted with a slight clearance from the surfaces of disc 20 and define, within chamber 19, a crescent-shaped work space for the compression.

The work space 19 becomes larger on one side of plate 30 and becomes smaller on the other side thereof during rotation in the direction of arrow 31, in such a way that the working medium inducted by suction from the supply conduit 21 is compressed and is forced outwardly through orifice 32 by way of valve 33 into space 34 whence it is finally abducted through conduit 22. For lubricating the surfaces, subjected to friction, between the flyweights 25 and 26 and disc 20, the lubricant fed through conduit 23 is forced into the lubricating grooves 35 and 36.

For the purpose of preventing chattering or other vibrations during starting or stopping the machine, a ring 37 having a hardness different from that of system I, is provided, and is pressed, by means of springs 38, to a predetermined degree against the pedestal or base 39, so that it is displaced, relatively to the pedestal 39 by the frictional forces, corresponding in degree to the degree of forcing.

Due to the flyweights 25 and 26 rolling upon the inner cylindrical surface of housing-part 18, knocking is prevented when the displacer body 24 rolls over the slot for the slide plate 30, so that the compressor operates substantially noiselessly. Arranged at one of the ends of the bolt of the displacer body 24 is a conical extension 40, which is spaced but a short distance from the extension 41 of shaft 14 so that the displacer body

24 can never come inwardly and occupy a central position in the work-chamber 24.

For ease and accuracy in machining the housing part 18, its inner cylindrical face is broached all around at once so that the two flyweights 25 and 26 can be accurately machined to the same diameter and so that their rolling motion takes place evenly both on the lower and on the upper side. In that case the disc 20 must be machined to the same diameter and is securely held in the casing part 18 by means of the radially-extending, conical studs 43.

The elastic suspension of 1, 2, etc. from ring 9 is effectuated in such a way that the point of intersection of the resultant forces acting upon the various systems is situated, relatively to each individual system, at least in the vicinity of the center 42 of the elastic main-suspension so that no knocks can come on the suspending means. The ring 37, also, is arranged in such a way that the thrusts delivered by it to the machine result in a central thrust point or impact-point which is situated in the vicinity of point 42 so that no knocks, thrusts, or other sudden forces can be delivered to the support 12 either on starting or stopping the compressor.

The embodiment of the invention above described merely serves to illustrate the principles of the invention, and various changes in the form, construction and arrangement of parts thereof may be made without departing from the invention, the scope of which is indicated in the appended claims.

I claim

1. In a machine for working optionally as pump and compressor, in both cases independently of stuffing boxes, the combination of a driving structure including an electro-motor rotor circumscribing the whole machine by being a body with a centric surface of revolution rotatable about its axis of symmetry; an intermediate structure arranged with its axis of symmetry displaced relatively to the axis of rotation of the rotor comprising at least the non-rotating part of the electro-motor and a pump casing containing the working chamber moving translatorily under the influence of the driving structure; and a structure for working on the fluid, said last structure being driven by the inertia effects caused by the said translatory motions of the intermediate structure, said driving structure and said intermediate structure being mutually so mounted as to place the axes of their motions substantially parallel.

2. A compressor in accordance with claim 1, in which all three structures are so arranged relatively as to place their axes of movement parallel to each other.

3. A compressor in accordance with claim 1, in which the translatorily moving structure and the structure for working on the fluid are arranged within the driving structure in such a manner that the resultant-weight is taken directly by the driving structure.

4. A compressor in accordance with claim 1, in which there is a fixed support for the driving structure, a gudgeon pin secured to said fixed support, the driving structure being journaled on said pin.

5. A compressor in accordance with claim 1, in which there is a fixed support for the driving structure, a bearing secured to said fixed support, and a journal for the driving structure on said fixed support.

6. A compressor in accordance with claim 1,

in which there are resilient members and the driving structure is suspended thereby.

7. A compressor in accordance with claim 1, in which the compressor has a main suspension point and the central impact points of the forces which arise as the resultants of the forces exerted upon any one of the structures by the other structures is situated for each individual struc-

ture in the vicinity of the main point of suspension of the compressor.

8. A compressor in accordance with claim 1, in which the driving structure is provided with a rotating housing bell-shaped and open at the bottom whereby to admit conduits for conveying the working medium and the lubricant. 5
